UNITED STATES PATENT OFFICE.

JOHN H. STOCKHOLDER AND WILLIAM A. GILES, OF NEW ORLEANS, LOUISIANA.

STEAM-BOILER SAFETY DEVICE.

Application filed October 18, 1923. Serial No. 669,364.

This invention relates to steam boiler safety devices wherein fusible plugs of metal are arranged in the water spaces of steam boilers or steam drums, and are intended to 5 melt at a predetermined condition of low water and excessive heat permitting the water and steam to escape and to sound an alarm or to act upon the furnace fire to quench the same in the manner usual in such 10 devices.

The object of this invention is the production of a safety device belonging to the class stated and having parts of special construction and arrangement whereby it is believed the cost of manufacture is materially 15 reduced, and the convenience of installation and certainty of operation increased with added effectiveness.

In the accompanying drawings the special 20 construction and arrangement of the parts of this invention are illustrated. Of the drawings, Fig. 1 represents a vertical section lengthwise of all the parts assembled. Fig. 2 is a cross-section on the line 2—2 of 25 Fig. 1. Fig. 3 is a bottom view of the casing near the end provided with the out-flow pipe, showing the base or projecting members of the fusible plug carriers. Fig. 4 is a side view of a modified form of this invention. 30

Throughout the drawings and description the same letter is used to refer to the same part.

Considering Figs. 1, 2 and 3 of the drawings, there will be noted a portion A of the crown sheet of a steam boiler, or other surface thereof subjected to heat. Upon the portion A, and within the water space of the boiler or drum, is placed a casing B of 35 such size and form as will permit its arrangement within the water space as desired. The casing has an out-flow pipe b which may obviously be led in any direction and may be of such length as may be required. The casing as usually constructed 40 has a number of thickened portions C and through the portions C openings are made and threaded to take the ring nuts or carriers D for the fusible plugs E. The carriers D have on the bottom the spaced members d and between them the spaces e. The members d are constructed to make an intimate contact, as close as may be with the heated portion A of the boiler, in order 45 that the temperature of each carrier may at all times be the same as that of the boiler

surface of A, the heat being conducted by metallic contact. The members d support the casing B and the plugs E near the surface of the boiler portion A, and in ordinary 50 service the steaming of the boiler causes more or less circulation of water through the spaces e, thereby preventing the fastening of the carriers D and the plugs E to the portion A by deposits of boiler scale or the like. It will be noted in Fig. 1 that the plug carrier D has a conical internal chamber corresponding in form to the fusible plug E. It will be observed further that the greatest 55 diameter of the chamber is a short distance above the bottom of the carrier D. Below the plug, the spaced members d have inwardly projecting portions engaging the plug to hold it in position in the opening 60 of the carrier D. The plugs E are of soft 75 metal and are usually run into the chamber of the carrier in a melted condition. The chamber in the carrier is designated by reference characters d' in the drawings, and the projecting portions of the spaced members by d². Of the two truncated conical 79 portions of the plug E, it is shown that the upper portion e' is the longer. The reason for this construction is that the pressure beneath the plug is relied upon to force the 85 plug into a steam tight fit in the chamber d' of the carrier, and greater surface of contact is desirable, while the lower portion of the plug E, designated by e², serves by reason of its engagement with the projecting 90 portions d² of the spaced members d to prevent the plug from dropping out should it have become loose and when the casing B is removed for any purpose. These applicants are fully aware of the practice, and 95 hold themselves at liberty to press the soft metal plugs E into the chambers d' of the carriers.

The modification illustrated in Fig. 4 is made up of like parts to those described, but 100 of somewhat different shape. The out-flow pipe is marked F, the body of the casing is designated by the letter G, and has side branches g and g'. The ring nuts H and fusible plugs J are the same as before with 105 the exception that the members h projecting from the base of the carriers are formed to fit a given heated boiler surface, such for example as the fire tube K. The circulation space j between the base members h will be 110 noted in Fig. 4.

The operation of the preferred form of

this invention and of the modification is the same. The carriers have at all times the temperature of the surface with which they are in contact, and if there should occur a condition of low water and excessive heat following therefrom, the plugs E soften and blow out into the casing, allowing the steam and water to escape by way of the out-flow pipes to any suitable alarm. The object of providing a plurality of carriers and plugs is to insure absolute certainty of operation and a higher margin of safety. As illustrated, it is customary to arrange the plugs with like axes thereof in the same plane passing through the casing.

Having now described this invention, and explained the mode of its operation, we claim:

In a steam boiler safety device, the combination with a casing having an outflow

pipe, the said casing being constructed for arrangement in the water space of a steam boiler and adjacent to a surface subjected to heat, of a plug carrier having a screw threaded engagement with the said casing, the said carrier having a conical opening therethrough, a fusible plug fitting the said opening in the carrier, the said carrier having spaced members projecting downwardly below the plug for contact with the heated surface whereby water may circulate below the plug, said spaced members having inwardly projecting portions engaging said plug to hold it in position in the said opening.

In testimony whereof we affix our signatures.

JOHN H. STOCKHOLDER.
WILLIAM A. GILES.
